PHOTOCHEMICAL PRODUCTION OF OLEFINIC HYDROCARBONS

Henry G. Schutze and Harry E. Cier, Baytown,
Tex., assignors, by mesne assignments, to
Standard Oil Development Company, Eliza-
beth, N. J., a corporation of Delaware

No Drawing. Application March 24, 1951,
Serial No. 217,402

11 Claims. (Cl. 204—162)

1
The present invention is directed to a method for producing olefins. More particularly, the invention is concerned with the production of mono-olefins from a paraffinic hydrocarbon.

The present invention may be briefly described as involving exposing a paraffinic hydrocarbon having from 2 to 6 carbon atoms in the molecule to a resonance frequency radiation in a reaction zone in which the resonance frequency radiation is of an intensity at least 0.1 watt per square centimeter of exposed reaction zone surface in the presence of a metal sensitizer at a reaction temperature and pressure at least atmospheric and for a time at least 0.5 second to form a product comprising olefins having a greater number of carbon atoms than the paraffinic hydrocarbon feed.

The temperature employed in the present invention may suitably range from about 100° F. to 750° F. with a preferred temperature in the range from about 200° to about 500° F. Temperatures lower than 100° F. have no particular effect on the course of the reaction but higher temperatures than the maximum may result in cracking reactions taking place.

The paraffinic hydrocarbon employed in the practice of the present invention should have from 2 to 6 carbon atoms in the molecule and may be illustrated by ethane, propane, the butanes, the pentanes and the hexanes. Normal butane forms the preferred feed stock of the present invention. Likewise the normal paraffinic hydrocarbons are preferred to the iso-paraffinic hydrocarbons. Normal pentane and normal hexane would be preferred to either isopentane or isohexane.

In practicing the present invention the paraffinic hydrocarbon should be exposed in a suitable reaction zone to a resonance frequency radiation of an intensity at least 0.1 watt per square centimeter of the exposed reaction zone surface. The resonance frequency radiation may suitably be in the range from 0.1 watt to 4 watts per square centimeter but higher intensities of radiation may be employed when such are available.

The time of contact for exposure of the paraffinic hydrocarbon in the practice of the present invention may range from 0.5 second to 5 minutes but a preferred range is from 1 second to 1 minute. It is undesirable to use higher contact times than the maximum because large size reaction vessels would be required.

The metal sensitizing agent employed in the present invention may be any metal which meets the conditions set out below, including proper

2
vapor pressure, light absorption characteristics, and energy content in the activated state. Whatever metal sensitizer is employed it is incorporated in the reaction mixture of hydrocarbons, and the mixture is subjected to radiant energy-containing frequencies which are capable of energizing the metal sensitizer. In selecting a metal sensitizer and a source of radiant energy for the reaction, the following conditions

10 must be met:

(A) The vapor pressure of the metal employed as a sensitizer must be sufficient to insure that metal vapor is present in the hydrocarbon mixture in a concentration sufficient to absorb the 15 activating light efficiently and to an extent that will permit rapid reaction to take place; conveniently, this vapor pressure is at least 0.001 mm. of mercury at a temperature below about 650° F.

20 (B) The radiant energy must be of a frequency that can be absorbed by the metallic sensitizer in its ground state in the hydrocarbon mixture. This frequency must correspond to at least one of the resonance lines of the metal sensitizer.

25 (C) The sum of the energy of the resonance frequency absorbed by the metal sensitizer and of the energy of the metal-hydrogen bond must correspond to an energy content equal to or in 30 excess of that required to rupture one of the paraffin C-H bonds.

While a number of metal sensitizing agents will fill some of the foregoing requirements, the preferred metal sensitizing agents in carrying out our invention are the metals of subgroup B 35 of group II of the periodic table, namely mercury, cadmium and zinc. While either of these metals may be employed in our process, mercury will be preferred because of its availability, vapor pressure, activation energy, and other peculiar properties.

In order to illustrate the resonance lines of the metallic sensitizers suitable for practice in the present invention, the following table is presented:

Table I

Element	Resonance lines, Å.
Hg.....	{ 2,537 1,850
Cd.....	{ 3,261 2,289
Zn.....	{ 3,076 2,139

The process of the present invention is not limited to any particular type of equipment. The reaction has been carried out satisfactorily in an annular reactor consisting of a cylindrical outer Pyrex jacket provided with an inlet at one end and an outlet at the other end, the inner cylinder emanating light of the desired wave length. For example, when it is desired to employ mercury as the metallic sensitizer, a mercury vapor lamp emanating light of 2537 Å. wave length is inserted as a concentric inner cylinder in the Pyrex jacket. When employing mercury as a sensitizer, the lamp should be operated in such a manner that an unreversed 2537 Å. line is obtained. A satisfactory lamp for such a purpose is, for example, a 15 watt germicidal lamp, or a lamp such as described in U. S. Patent 2,473,642 to Found et al.

When cadmium is used as the metallic sensitizer, a cadmium lamp may be employed. The reactor jacket may be surrounded with a suitable heating means such as an electric heater or a furnace. In converting a paraffinic hydrocarbon, the paraffinic hydrocarbon feed is vaporized and introduced into the jacket through the inlet, and the products of reaction are withdrawn through the outlet. In carrying out a mercury-sensitized reaction, a satisfactory method of maintaining the mercury sensitizer in the reactor has been to place a small amount of metallic mercury into the reactor jacket prior to the beginning of the reaction. Other satisfactory methods of introducing metal sensitizer are known; for example, a carrier stream, consisting of the vaporized hydrocarbon feed, or a portion thereof, or an inert gas, such as nitrogen, may be passed through a vessel containing the metal sensitizer in the liquid or vapor state prior to passing said carrier stream into the reactor.

Although it is desirable to employ a purified hydrocarbon, the present invention is not limited to such. The feed stock may include two or more paraffinic hydrocarbons from which olefins having a greater number of carbon atoms than the feed stock may be produced. It is desirable that the paraffinic hydrocarbon not be contaminated with impurities which may react with the feed or sensitizer to produce undesirable contaminating compounds in the product. For example, water vapor in low concentration may not be harmful to the reaction when a mercury sensitizer is employed but it may be harmful when cadmium is used as the sensitizer because cadmium is oxidized by water vapor. Also it is desirable to exclude reactive compounds other than the hydrocarbons because such compounds may cause undesirable side reactions to take place which will produce other compounds than the desired product.

The effluent leaving the reaction zone, in the practice of the present invention, may be subjected to condensation to recover the feed and product in the liquid phase, and hydrogen and other non-condensibles, remaining in the gas phase and being easily separable therefrom. The condensed liquid phase may then be subjected to fractional distillation to recover a desired fraction and the olefins may then be recovered from a segregated fraction by suitable chemical treatment which is well known in the art. For example, it is known that olefins react with sulfuric acid from which they are recoverable as such.

The invention will be further illustrated by reference to the following examples.

A substantially pure normal butane feed con-

5 taining about 98% normal butane and 2% other paraffins was charged to a reaction zone, such as that described before, including a 15 watt germicidal lamp. The temperatures employed ranged for one run from 120° to 130° F. and in the second run the temperature was 133° F. The contact time during which the butane was exposed to the radiation was around 4 minutes. Olefins were identified in both products having from 6 to 12 carbon atoms in the molecule. The olefins averaged about 8 carbon atoms in the molecule.

Additional runs were made in an 80 watt 2537 mercury type lamp with normal butane as a feed stock. The temperature in the reaction zone was 125° F.; a yield of olefins of about 5% was found in the product having from 6 to 12 carbon atoms in the molecule.

In additional runs normal butane was exposed in a reaction zone including an 800 watt mercury lamp. The time the butane was exposed in these runs ranged from 0.5 to 3.3 seconds, the temperature remaining constant at 250° F. The results of these runs are shown in Table II.

Table II

Reaction temp., ° F.	250	250	250	250	250
Residence time, seconds	3.3	1.1	0.8	0.5	0.25
Deparaffinized product:					
Paraffins	63	80	84	83	89
Olefins	14	10	9	8	5
Others	23	10	7	9	6
Intensity of radiation, watt per square centimeter of reaction zone surface	0.5	0.5	0.5	0.5	0.5

From the data in Table II, it will be seen that the olefin concentration increases as the residence time increases at a constant intensity of radiation.

Another run was made in a 2400 watt mercury pool lamp in which gaseous normal butane which had been saturated with mercury was charged thereto. The intensity of radiation was about 0.1 watt per square centimeter of reaction zone surface. The temperature in the reaction zone was above 600° F. The time the butane was exposed was about 3 seconds. The olefin content of the product was about 43% by volume. The product had from 6 to 12 carbon atoms in the molecule.

When employing mercury as a metal sensitizer, the product may be found to contain small quantities of mercury carried out from the reaction zone. It may be desirable, therefore, to recover this mercury and the mercury may be separated by cooling the effluent from the reaction zone or the effluent may be passed over a suitable bed of amalgamating material to remove mercury from the product.

In the foregoing examples, the runs were carried out by vaporizing the feed and heating it to a reaction temperature and pressure. The feed was introduced into the inlet of an annular reactor of which a mercury lamp formed the inner cylinder and a Pyrex glass jacket formed the outer cylinder. The lamp employed has an energy output of over 90% of the emitted radiation in the unreversed 2537 Å. line. It was convenient to place a small amount of liquid mercury in the annulus to supply mercury vapor to the hydrocarbons to act as a metal sensitizer for the reaction in the gases where the feed stock was not previously saturated with mercury. During the reaction the jacket was heated externally to maintain reaction temperature. Pressures were substantially atmospheric. The feed was

continuously introduced in the inlet and product continuously withdrawn from the outlet. The reactor outlet was passed through condensers to recover a liquid phase and a gas phase which were subsequently recovered and analyzed to determine their composition.

It is not understood exactly what mechanisms are involved in the formation of olefins from low molecular weight paraffins. It is possible that a metal sensitized photochemical reaction is involved in which mercury is excited by resonance radiation and the excited mercury then causes a paraffinic hydrocarbon molecule to form an alkyl radical and hydrogen. One of the alkyl radicals may then combine with a paraffinic hydrocarbon molecule to form the high molecular olefin having a greater number of carbon atoms than the paraffinic hydrocarbon feed. As another postulate, it is possible that the excited mercury causes the formation of an alkyl radical from the paraffinic hydrocarbon and that two of the alkyl radicals react to form a higher molecular weight paraffin from which hydrogen is split off to form the higher molecular weight olefin having a greater number of carbon atoms than the paraffin hydrocarbon feed. Regardless of the mechanism involved in the formation of an olefin having a greater number of carbon atoms than the normal paraffin feed, it is to be understood that our invention involves subjecting a paraffinic hydrocarbon to the foregoing conditions to cause the formation of the higher molecular weight olefins as has been described.

The nature and objects of the present invention having been completely described and illustrated, what we wish to claim as new and useful and to secure by Letters Patent is:

1. A method for producing olefins which comprises exposing a continuous stream of a paraffinic hydrocarbon having from 2 to 6 carbon atoms in a reaction zone, having a surface exposed to a resonance frequency radiation, to a resonance frequency radiation in the range from 0.1 to 4 watts per square centimeter of exposed reaction zone surface in the presence of a metal sensitizer selected from the group consisting of mercury, cadmium, and zinc at a temperature in the range from 100° to 750° F. at a pressure at least atmospheric for a time in the range from 0.5 second to 5 minutes to form a product comprising olefins having a greater number of carbon atoms than said paraffinic hydrocarbon, and recovering said product, said resonance frequency radiation corresponding at least to one of the resonance lines of said sensitizer.

2. A method in accordance with claim 1 in which the metal sensitizing agent is mercury.

3. A method in accordance with claim 1 in which the metal sensitizing agent is zinc.

4. A method in accordance with claim 1 in which the metal sensitizing agent is cadmium.

5. A method for producing olefins which comprises exposing a continuous stream of a paraffinic hydrocarbon having from 2 to 6 carbon atoms in a reaction zone, having a surface exposed to a resonance frequency radiation, to a resonance frequency radiation of an intensity in the range from 0.1 watt to 4 watts per square centimeter of exposed reaction zone surface in the presence of mercury at a temperature in the range from 200° to 500° F. at a pressure substantially atmospheric for a time in the range

from 1 second to 1 minute to form a product comprising mono-olefins having a greater number of carbon atoms than said paraffinic hydrocarbon, and recovering said product, said resonance frequency radiation corresponding to one of the resonance lines of mercury.

6. A method for producing olefins which comprises exposing a continuous stream of a butane in a reaction zone, having a surface exposed to a resonance frequency radiation, to a resonance frequency radiation of an intensity in the range from 0.1 watt to 4 watts per square centimeter of exposed reaction zone surface in the presence of mercury at a temperature in the range from 200° to 500° F. at a pressure substantially atmospheric for a time ranging from 1 second to 1 minute to form a product comprising mono-olefins having a greater number of carbon atoms than said butane, and recovering said product, said resonance frequency radiation corresponding to one of the resonance lines of mercury.

7. A method for producing olefins which comprises exposing a continuous stream of a paraffinic hydrocarbon having from 2 to 6 carbon atoms in a reaction zone, having a surface exposed to a resonance frequency radiation, to a resonance frequency radiation of an intensity in the range from 0.1 to 4 watts per square centimeter of exposed reaction zone surface in the presence of a metal sensitizer selected from the group consisting of mercury, cadmium, and zinc at a temperature in the range from 200° to 500° F. for a time ranging from 0.5 second to 5 minutes and at a pressure at least atmospheric to form a product comprising mono-olefins having a greater number of carbon atoms than said paraffinic hydrocarbon, recovering said product, and separating mono-olefins therefrom, said resonance frequency radiation corresponding at least to one of the resonance lines of said sensitizer.

8. A method in accordance with claim 7 in which the metal sensitizing agent is mercury.

9. A method in accordance with claim 7 in which the metal sensitizing agent is zinc.

10. A method in accordance with claim 7 in which the metal sensitizing agent is cadmium.

11. A method in accordance with claim 7 in which the paraffinic hydrocarbon has at least 4 carbon atoms in the molecule.
